Primary Examiner — Susan Bennett Hattan*Assistant Examiner* — Marie Fast Horse(74) *Attorney, Agent, or Firm* — Michael Best & Friedrich LLP(57) **CLAIM**

We claim the ornamental design for a carrier tray, as shown and described in the figures.

DESCRIPTION

FIG. 1 is a perspective view of carrier tray, embodying aspects of the invention.

FIG. 2 is a front view of the carrier tray shown in FIG. 1.

FIG. 3 is a side view of the carrier tray shown in FIG. 1; and,

FIG. 4 is a bottom view of the carrier tray shown in FIG. 1.

The Dash-Dot broken line depicts the bounds of the claim while all other broken lines in the drawings depict environmental subject matter only. All broken lines form no part of the claimed design.

The carrier tray is not shown from the rear, as this surface is flat and devoid of surface ornamentation, and does not form part of the claimed design.
